LUBRICATING AND GUIDING MEANS FOR SPINNING MECHANISMS.

Archie Clocker and George F. Macfarlane,
Wilkes-Barre, Pa.

Application August 27, 1927. Serial No. 215,872

6 Claims. (Cl. 118—59)

The present invention relates to a new and improved lubricating and guiding means for spinning machines.

More particularly the invention relates to improved lubricating and guiding means for travellers utilized in well known types of spinning machines for the production of twisted threads used in the manufacture of cloth, fabrics, and the like.

10 In the present commonly used spinning machines for the twisting of silk and like thread, the threads to be twisted are guided from spools over rotating travellers, twisted into single strands and wound on bobbins. These travellers 15 rotate against a metallic surface at high speed, and consequently ordinarily wear rapidly, thus requiring frequent replacements. In order to lubricate the travellers, as at present used, it is the practice to apply lubricant approximately 20 twice a day in a manner resulting in a considerable waste of lubricant and labor. The common manner of application of lubricant is such that excess lubricant finds its way up on the thread guiding sections of the travellers, discoloring the thread.

25 In operation of silk spinning machines, kinks frequently form in the twisted threads and lay over on the surfaces to which the lubricant for the traveller has been provided as the bobbins 30 stop, absorbing oil and further discoloring the twisted thread. The present manner of applying the lubricant is inefficient and only a small percentage of the lubricant used actually reaches the traveller with the result that the life of the travellers with the prior arrangements is about 35 three days. The discolorations caused by the lubricant are almost impossible to remove from the twisted threads, thus making the weaving of light shades of fabrics and cloth from threads spun by the prior machines, a difficult and costly 40 operation, as heavy losses occur due to the amount of goods which is damaged and which must be dyed dark in color so that the discolorations will not be visible.

45 Accordingly, a primary object of our invention is to provide novel guiding and lubricating means for travellers in spinning mechanisms which are of such nature that the threads are protected from discoloration and a proper 50 amount of lubricant with a minimum of labor is automatically applied to the travellers. In practice the application of our invention to standard spinning machines has materially extended the life of the travellers without the 55 necessity of frequent application of lubricant

the application of about fifteen drops of oil about once a month providing ample lubricant, materially increasing the life of the spinner, and substantially reducing the cost of lubrication and maintenance. At the same time, no 60 excess lubricant is present and the travellers remain free of oil as well as the exposed surface of the lubricating ring thus making it impossible for kinks in the thread to come into contact with any lubricant. With our improved 65 device, it has become possible to spin pure white threads without discoloration due to lubricant, making the production of pure white and the light shades of high grade silks, and other cloths, readily possible.

70 Further objects of our invention are such as will appear from the following detailed description of a preferred embodiment thereof and as particularly pointed out by the terms of the appended claims.

75 As shown in the drawing:

Figure 1 is a top plan view of one form of my invention.

Figure 2 is a longitudinal sectional view taken on line 2—2 of Figure 1.

Figure 3 is a top plan view of the ring holder.

Figure 4 is a top plan view of the lubricating pan.

Figure 5 is a top plan view of the ring, and

Figure 6 is a more or less diagrammatic view 85 showing a method of applying my invention in practice.

Referring to the drawing by reference characters, in which like characters designate like parts, 10 designates as a whole our improved 90 guiding and lubricating device for the commonly used travellers in standard types of spinning machines. The guiding and lubricating device 10 comprises a securing member or ring holder 11 provided with diametrically opposite slotted se- 95 curing lugs 12 disposed in the plane of the body portion of the holder and outwardly projecting equally spaced yieldable supporting members 13 struck up from the outer perimeter thereof.

100 Adapted to be supported on the outer surface of the ring holder 11 is a lubricating pan 14 which comprises a base portion 15 equal in width to that of the ring holder and outwardly projecting annular inner and outer walls 16 and 17 respectively. Adapted to seat on the outer flange 105 17 of the lubricating pan 14 is a ring 18 which as more clearly shown in Figure 2 is inwardly dished, that is, the inner edge of the ring is in a plane below that of the outer edge thereof.

110 The three members above described comprise

our improved guiding and lubricating device and are assembled as shown in Figure 2. The lubricating pan 14 is placed upon the ring holder 11 within the supporting members 13 thereof which 5 retain the pan against movement thereon, after which the ring 18 is placed on the pan with the outer edge thereof in engagement with the outer flange 17 and the inner edge thereof in spaced relation to the inner wall 16 defining an annular 10 opening 19.

In Figure 6 is shown the application of our invention to a well known form of spinning machine comprising the traversing bar 21 provided with openings 22 to which bar the guiding and lubricating devices are secured in register with the openings 22 by means of bolts 23 extending through the bar and slotted lugs 12 of the ring holders 11.

Disposed beneath the openings 22 in the traversing bar are bobbin spindles and driving pulleys 24 which are suitably supported for rotation from the frame of the machine and are rotated at a high speed by the driving belt 25. Bobbins 26 upon which the twisted thread is to 25 be wound are supported on the spindles and rotated by pulleys 24 at high speed.

The threads 27 to be twisted and wound on the bobbins 26 are fed from suitably supported rollers 28 through the wire loops 29 and are then 30 passed around the corresponding travellers 30 to the bobbins 26 as indicated.

As is well known, in operation of devices of this character, the rotation of the bobbins and the action of the threads 27 causes rotation of the traveller 30 twisting the threads into a single strand which is wound on the bobbins. As the rotation of the bobbins and the winding of the twisted thread proceeds, the traversing bar 21 is reciprocated vertically causing the winding of 40 the twisted thread on the bobbins in uniform manner.

In prior spinning machines the ends of the travellers engaged and were guided by a metallic member in the form of a metallic ring and it has 45 been the practice to apply lubricant on the upper surface of such ring to lubricate the travellers. As a result of this method of applying lubricant, excess lubricant finds its way over the ends of the travellers to the thread guiding sections thereof and discolors the thread. Furthermore, when 50 the spindles on which the bobbins are supported stop, kinks form in the twisted thread due to the movement of the traversing bar and frequently lay over on the upper surfaces of the rings absorbing the oil and causing additional discoloration 55 of the thread.

In accordance with our improvement herein disclosed, a small amount of lubricant is supplied in the pan 14, which as shown is disposed beneath the ring 18, the inwardly projecting portions of the travellers extend within the annular opening 19 and the ends thereof in operation engage the inner surface of the ring. As is well known a spinning machine is stopped several times a day at which time the travellers fall away from engagement with the under surfaces of the rings and the ends thereof will dip into the lubricant in the pan 14. When the machine is again put into operation the under surfaces of the rings will be lubricated by means of the lubricant carried by the ends of the travellers, while at the same time there is no possibility of any lubricant reaching the thread guiding sections of the travellers or the outer 70 surfaces of the ring.

Thus in accordance with our invention, a small amount of lubricant, in practice about fifteen drops once a month, is supplied to the pan 14 after which the lubrication of the travellers need be given no attention and the usual operations of spinning can proceed without any possible danger of discolorations in the thread due to the lubricant.

What is claimed and desired to be secured by U. S. Letters Patent is:

1. A guiding and lubricating device for the travellers of spinning machines comprising an annular lubricant receiving channel member, a traveller guide extending inwardly from one wall of said annular lubricant receiving channel member, and an annular opening between said guide and the other wall of said annular lubricant receiving channel member adapted to receive and guide the ends of the traveller.

2. A guiding and lubricating device for spinning machines comprising a ring holder having slotted attaching lugs and a plurality of equally spaced supporting members, a lubricant supplying member supported on said ring holder within the supporting members thereof, and a lubricating and guide ring supported on said lubricant supplying member and retained thereon by means of said supporting members.

3. A guiding and lubricating device for spinning machines comprising a ring holder having diametrically opposite slotted securing lugs and outwardly projecting equally spaced supporting members, an annular lubricant supplying member supported on said ring holder and retained thereon by said supporting members, and a lubricating and guide ring supported on said lubricant supplying member and retained thereon by said supporting members.

4. A guiding and lubricating device for the traversing bar of a spinning machine comprising a ring holder adapted to be secured to said traversing bar, said ring holder being provided with a plurality of outwardly projecting yieldable supporting members, a lubricant supplying channel member adapted to be supported on said ring holder and retained thereon by said supporting members, and a lubricating and guide ring adapted to have one edge thereof rest on one of the flanges of said channel member and retained thereon by said supporting members.

5. A guiding and lubricating device for the travellers of spinning machines comprising an annular channel shaped lubricant reservoir, a traveller guide ring having one edge thereof seated on one of the flanges of said channel shaped lubricant reservoir, and the opposite edge thereof spaced from the opposite flange and overhanging said reservoir, the said opposite edge and opposite flange defining an annular traveller guiding opening whereby upon operation of the machine the ends of the traveller engage the inner surface of the guide ring and whereby upon stopping the machine said ends dip into the lubricant in said lubricant reservoir.

6. A spinning ring comprising a shell having spaced inner and outer walls, an oil well formed between said walls, an annular seat formed about said well, a ring removably positioned on said seat, and a bar-traveller within the ring.
